PRODUCTION OF AMINES OF HIGH MOLECULAR WEIGHT

Adolf Grün, Basel, Switzerland, assignor, by mesne assignments, to Bohme Fettchemie-Gesellschaft m. b. H., Chemnitz, Germany, a corporation of Germany

No Drawing. Application March 14, 1935, Serial No. 11,073. In Germany March 17, 1934

8 Claims. (Cl. 260—127)

This invention relates to the production of amine compounds containing alkyl radicals of high molecular weight and more particularly to processes of producing amines having an alkyl radical of at least 8 carbon atoms from α -amino fatty acids, the acyl radicals of which contain one more carbon atom than the alkyl radical obtained.

In its broader aspects, the present invention comprehends decomposing substituted α -amino high molecular weight fatty acids into high molecular alkyl amines by heating the acids under conditions which avoid objectionable side reactions and decompositions whereby almost quantitative conversions may be obtained. This result can be very satisfactorily accomplished by heating the acids in the presence of an inert solvent or diluent liquid which remains as a liquid at the temperature necessary for the decomposition. When the process is carried out at atmospheric pressure the solvent or diluent must possess quite a high temperature boiling point, such for example, as possessed by paraffin oil or liquid petrolatum.

When a solvent of this nature is employed, the temperature at which the decomposition occurs can be controlled within narrow limits while avoiding local overheating and undesired and costly side reactions leading to carbonaceous decomposition products.

The process is applicable to the direct production of substituted amines, i. e., secondary and tertiary amines containing alkyl radicals of high molecular weight from substituted α -amino fatty acids containing acyl radicals of high molecular weight. The substituting radicals may be aliphatic, aromatic, cycloaliphatic, heterocyclic or any combination of the same radicals or different radicals as dimethyl and ethylphenyl, respectively.

Considered from a different point of view, the invention might be considered a method converting high molecular weight fatty acyl radicals into alkyl radicals of about the same molecular weight while contained in amine compounds. The acyl radicals convertible by the present process include, for example, capric, lauric, myristic, palmitic, stearic, arachic and like acids.

A very satisfactory method of obtaining the α -amine fatty acids treated in accordance with the present invention is by reacting α -halo fatty acids with amines. For example, alkyl-aryl-amino fatty acids may be easily obtained by reacting halo fatty acids with mono or dialkyl-aryl-amines, said alkyl radicals preferably being of low molecular weight, for instance, dimethyl aniline. Dur-

ing the reaction hydrogen halide or an alkyl halide is liberated and an alkyl-aryl amino fatty acid formed. Failure to obtain 100% conversion in this reaction is believed probably due to the shifting of an alkyl radical to the carboxylic group, but the acid may be made available and returned to the process by simple saponification.

In producing the alkyl amines from the amino fatty acids in accordance with the present invention the amino fatty acid is preferably first mixed with the particular inert solvent chosen and the mixture heated at atmospheric pressure to a temperature of from about 130 to 280° C. Commencement of the decomposition may be noticed by the evolution of carbon dioxide and its completion by cessation of its evolution.

Example

Three hundred and seventy-five parts by weight of α -anilino stearic acid are dissolved in ten times the amount by weight of paraffin oil during heating in which the temperature is slowly increased.

When a temperature of approximately 140° C. is reached a considerable ebullition of gas commences. At a temperature of about 200 to 220° C. gas is evolved at a very rapid rate, but decreases as the temperature is increased. When a temperature of about 280° C. is reached no more gas is liberated. By proceeding in this manner practically quantitative results are obtained. For each molecule of acid decomposed one molecule of carbon dioxide is liberated. At the conclusion of the operation the paraffin solution is light yellow in color but becomes light brown when cool and is at all times completely clear. In order to isolate the heptadecylaniline, the paraffin solution is diluted with an equal volume of ether and introduced into a solution of hydrochloric acid during constant stirring. Heptadecylaniline hydrochloride forms and precipitates out as a white, fine crystalline substance. If the solution becomes too thick for proper treatment it may be diluted by the addition of more ether. When the reaction with hydrochloric acid is complete, the mass is permitted to cool after which the liquid is drawn off suitably by suction leaving the white crystalline hydrochloride which should be further washed with ice cold ether. The aniline base may be recovered by suspending the hydrochloride in hot water and adding sodium hydroxide during stirring until the mass becomes alkaline. An oily upper layer comprising the aniline base forms and after cooling is removed and dissolved in ether. The ether is washed out of the mass by means of water until neutrality is reached, the mass then

being dried and any ether remaining being distilled off. The base thus obtained is in a substantially pure form.

- 5 In a similar manner other amino fatty acids such as for example, diethyl amino stearic acid, monomethyl anilino lauric acid and other analogous compounds which may be derived from cycloaliphatic or heterocyclic bases can be converted into corresponding amines.
- 10 10 It should be understood that the present invention is not limited to the specific compounds and conditions herein specified, but that it is limited only by the terms employed in the appended claims.
- 15 15 I claim:
1. The process of producing amines of high molecular weight which comprises decomposing by the use of heat in the presence of an inert diluent non-volatile at the temperatures employed
  - 20 20 a substituted α -amino fatty acid containing an acyl radical of more than 8 carbon atoms substantially only into a substituted α -amino alkyl compound in which the alkyl radical contains one less carbon atom than the acyl radical, and into carbon dioxide.
  - 25 25 2. The process of producing amines of high molecular weight comprising heating a substituted α -amino fatty acid containing an acyl radical of high molecular weight in the presence of an inert diluent of a sufficiently high boiling point to remain in a liquid state at the temperatures employed, until reaction takes place with evolution of carbon dioxide.
  - 30 30 3. The process of producing amines of high molecular weight comprising adding a substituted α -amino fatty acid containing an acyl radical of more than 8 carbon atoms to an inert diluent of a sufficiently high temperature boiling point to remain in liquid state at the temperatures of the
  - 35 35 40 40 4. The process of producing amines of high reaction and heating the mass until carbon dioxide is given off.

molecular weight comprising heating an alpha-amino fatty acid compound of the general formula

5

10

wherein R is an aliphatic hydrocarbon of at least 8 carbon atoms, R₁ is selected from a hydrogen atom, and R₂ as well, from an aliphatic, an aromatic, and a cycloaliphatic radical, with an inert diluent of a sufficiently high temperature boiling point to remain in liquid state at the temperatures of the reaction until such compound decomposes into a compound of the general formula

15

and carbon dioxide.

5 20 25 2. The process of producing amines of high molecular weight comprising heating an α -anilino high molecular weight fatty acid to a temperature at which the same decomposes into an alkyl aniline, the alkyl radical of which contains one less carbon atom than the acyl radical of the fatty acid, and into carbon dioxide in the presence of an inert diluent which remains in the liquid state at the temperatures employed.

6. The process as described in claim 5 wherein the compound treated is α -anilino stearic acid.

7. The process of producing amines of high molecular weight comprising heating a diethyl alpha-amino fatty acid in which the acyl radical contains more than 8 carbon atoms in the presence of paraffin oil to a temperature at which carbon dioxide is given off.

8. The process as described in claim 7 wherein the material treated is diethyl alpha-amino stearic acid.

ADOLF GRÜN.
